United States Patent Office.

PETER S. HOE, OF NEW YORK, N. Y.

Letters Patent No. 99,192, dated January 25, 1870.

IMPROVEMENT IN BATTERIES FOR ELECTROTYPEING.

The Schedule referred to in these Letters Patent and making part of the same.

I, PETER S. HOE, of the city, county, and State of New York, have invented a new and improved Battery for Electrotypers' Use, of which the following is a specification.

Nature and Objects of the Invention.

My invention relates to batteries used in electrotyping, &c., and has for its object the construction of a battery that will resist the action of the fluids it is intended to contain, will be indestructible in its character, and can be easily cleansed, as will be fully described hereafter.

Description of the Accompanying Drawings.

Figure 1 is a perspective view of my improved battery, with the sides partly removed in order to show its construction, and

Figure 2 is a top view of the same.

General Description.

The parts A, B B, C C, which form the bottom, side, and end-pieces of the trough, are cut of the desired size, from plate-glass.

The plate A, which forms the base, is provided with two longitudinal grooves, b b, into which the side-plates B B fit, and also with two transverse grooves, c c, which receive the end-plates C C, which also fit into the grooves d d in the side-plates B B.

The plates are secured together by means of the

rods E and F, which pass through holes drilled in the side and base-plates, and the nuts e and washers f. The washers, on the ends of the bolt-rods, are made of elastic material, in order to provide for any expansion or contraction that may take place, and they may be constructed of brass, steel, or other material that possesses the requisite quality of elasticity.

The grooves into which the ends of the plates are received, are coated with wax, or other substance that will answer the purpose, in order to prevent leakage; but to more effectually prevent the loss of any fluid, the battery, when completed, is placed in a box, G, and the space between the two is filled with paraffine or similar material, impervious to fluids.

Claims.

I claim, as my invention—

1. As a new and improved article of manufacture, a battery constructed of glass, substantially in the manner and for the purposes set forth and specified.
2. The combination, with a battery constructed of glass, of the case, lined with paraffine or similar material, substantially as described, and for the purposes specified.

PETER S. HOE.
